UNITED STATES PATENT OFFICE

RALPH G. WHITLOCK, OF LOS ANGELES, CALIFORNIA, ASSIGNOR TO RALPH G. WHITLOCK PATENTS, INC., OF LAS VEGAS, NEVADA, A CORPORATION OF NEVADA

DRIVE FOR A PRINTING MEMBER, INKING DEVICE, AND GUARD

Application filed February 23, 1929. Serial No. 342,091.

This invention relates to means for indicia printing so called "metered permit mail" and more particularly to a movement for time relating the printing member and a guard therefor.

Among the objects of my invention is to positively relate the cycle operations of the printing member and the guard whereby to obtain absolute coordination throughout their relative and various functionate movements, and to prevent unauthorized movements of the printing member.

My improvements consist in the novel construction, arrangement and combination of parts as hereinafter fully, clearly and concisely described, definitely pointed out in my claims, and illustrated by the accompanying drawings, (2 sheets) in which—

Fig. 1 is a longitudinal sectional elevation of a printing press constructed in accordance with my invention.

Fig. 2 is a transverse sectional elevation, taken substantially on the line 2—2 of Fig. 1, showing the movement for the printing member.

Fig. 3 is a similar elevation taken substantially on the line 3—3 of Fig. 1, showing the movement for the guard.

The machine, generally may be any device having recording mechanism to be set by the postmaster for a given number of impressions and which automatically locks when such impressions have been exhausted as for example, the machines shown in my applications, 25 Printing Press, Serial No. 40,631, filed June 30, 1925, and Meter Press, Serial No. 319,147, filed November 13, 1928. Inasmuch as the referred to record mechanism and the automatic lock form no part of the 40 present invention, except in combination, I will omit their detailed illustration and description.

Referring to the drawings, by numerals, 10 designates a casing in which there is a main, or driven, shaft 11 for the movements of the printing member 12 and the printing member guard 13.

Carried on the shaft is a gear element 14 forming part of a recording mechanism and 50 lock and a unidirectional device 15, such as

are described in the applications referred to.

Formed in the casing there is a mouth 16 through which the mail pieces, or letters, are fed to receive impressions and carried by the casing and exposed by said mouth is a platen 17.

Within the casing opposite to the platen is a track, or guide, comprising opposed rails 18, fixed to the sides of the casing, between, or in which, is mounted a slide, comprising spaced bars, or elements 19, and to which slide is secured the recited printing member 12.

A cam 20, of circular shape, and having a diameter substantially equal to the spacing of the recited bars 19 is eccentrically mounted on the shaft 11 and fixed to rotate therewith as by the collar 21 and set screw 22. To facilitate the placement of the cam relative to the slide bars 19, and to cooperate with the set screw 22 to prevent play in the cam I provide a flange 23 on each bar 19, and to, at least partially, compensate for variable thicknesses of mail pieces, I interpose a cushion 24, such as rubber, between the printing member and its carrier, the slide.

The guard 13 for the printing member comprises a wall 25, which surrounds, or partially surrounds, the printing member, 80 and a support, for the walls, formed as a pair of arms 26 integral with the walls and mounted to rock, as upon pivots 27, in a path comprehending the path of the printing member at all times.

Carried by the guard, preferably upon an arm 28, extending between the arms 26, is a roll 29 and carried on the shaft 11 to rotate therewith opposite to the roll is a face cam 30, having a groove, or roll path 31, as shown 90 in Fig. 2.

An inking device is provided and arranged for movement into and out of the path of the printing member, by preference such device includes an inking pad 32, at whose sides 95 there are keys 33 for riding in tracks, or ways, 34 formed in, or carried by, the arms 26 of the guard and a link motion 35 connecting the pad with the guard, as best shown in Fig. 1.

As best shown in Fig. 3 the sides of the cam groove comprise five distinct lengths, which in the order of action upon the roll 29, as indicated by the direction arrow, are first, a length 36, bearing such tangential, or angular, relation to the edge of the cam 20 shown by dotted lines in Fig. 3, for the operation of the printing member, as to cause an initial movement of the guard prior to 10 perceptible movement of the printing member to the end that the inking device is freed from, or moved to clear the type face.

Following the length 36 is a second length 37 bearing such angular relation to the edge 15 of the cam 20, as to cause the guard to be brought to rest upon the platen, or upon a mail piece supported thereon in advance of the movement of the printing member to the plane of impression, to the end that the 20 guard box surrounds (protects) the printing member during all of its movement to print, or toward the platen.

Following the length 37 is a third length 38 substantially concentric to the shaft, 25 which functions to hold the guard, with pressure, on the platen, or mail piece during the entire impression interval.

Following the length 38 is a length 39, which is substantially the physical opposite 30 of the length 37 and which functions to move the guard in a restoring direction in advance of the movement of the restoring movement of the printing member, and finally, following the length 39 there is a length 40, which is substantially the physical opposite 35 of the length 36, and which functions to cause the ink pad to be brought to engage the type face with percussion whereby to effect substantially uniform and clean inking of the 40 entire type face.

The various cam lengths coact with the link motion to first move the guard toward the platen to effect separating the ink pad from the type face; then by continued movement of the guard cause the ink pad as separated from the type face to be withdrawn in a path at substantially a right angle relative to the path of the printing member, then by continued movement of the guard in a guard restoring direction return the pad still separated from the type face to the path of the printing member and finally cause the pad to be rapidly moved in a path substantially paralleling the path of the printing member and brought as by impact to position against the type face.

The means, which translates the rotary motion of the main driven shaft to linear or reciprocating motion of the printing member and comprising the described cam and spaced bars of the printing member slide, prevents any movement of the printing member, except by rotation of the shaft and thereby reduces to a minimum unauthorized im-

pressions from the type, or indicia, of the printing member.

The form of the device illustrated and described herein is submitted in accordance with statutory requirement by way of exhibiting one form of embodiment of my invention. Various changes, alterations or modifications of the structure may be made without departure from my invention as defined in the following claims.

I claim:

1. The combination of a reciprocable printing member; an inking device, a movable guard, and means operable by the guard for initially moving the inking device in a direction substantially aligned with the path of the printing member to clear the inking device from the type face of the printing member, then bodily move the cleared inking device first out of and then into the path of the printing member and finally abruptly move the inking device in a direction aligned with the path of the printing member.

2. In a drive mechanism, a casing having a platen, a rotatable shaft, a printing member, an inking device, a guard, means relating the shaft and printing member, means comprising a face cam rotatable with the shaft, a roll carried by the guard, and a link motion between the guard and the inking device whereby there is effected positive synchronization between the printing member, the guard and the inking device.

3. In combination a printing member; a support for said printing member; guide means for said support; a guard; pivotally mounted arms connected to said guard and provided with track means; an inking member slideably guided by said track means; a rotatable shaft; means connected to said shaft for moving the inking member from the type face of the printing member and for moving the guard relative to said printing member; and means connected to said shaft for providing a constant drive relation between said shaft and printing member.

4. In combination: a casing having a printing throat formed therein; a shaft extending into said casing to a point opposite said throat; a non-reverse mechanism permitting rotation of said shaft in a single direction only; a printing member between said shaft and said throat; a platen on the opposite side of said throat from said printing member; guard means to prevent fraudulent impressions being secured from said printing member; means connecting said shaft to said printing member and guard means to positively move said member and guard means through a printing cycle; and means for driving a register for counting said printing cycles by direct connection with said shaft.

5. A combination as in claim 16 having a second guard member disposed alongside said

printing member and adapted to move into said printing throat in advance of said printing member and hold an object to be printed against said platen; and means for positively operating said second guard member from said shaft.

In testimony whereof, I hereunto affix my signature this 15th day of February, 1929.

RALPH G. WHITLOCK.

CERTIFICATE OF CORRECTION.

Patent No. 1,870,430.

August 9, 1932.

RALPH G. WHITLOCK.

It is hereby certified that error appears in the printed specification of the above numbered patent requiring correction as follows: Page 2, line 129, beginning with the words "5. A combination" strike out all to and including "shaft.", in line 6, page 3, comprising claim 5, and insert the following as claim 5:

5. In combination: a casing having a printing throat formed therein; a platen opposite one side of said throat; a printing member opposite the other side of said throat; a guard member normally disposed between said printing member and said throat; a shaft extending into said casing; and means actuated by said shaft to positively position said guard member between said printing member and said throat when said printing member is retracted into inactive position, to positively withdraw said guard member from between said printing member and said throat during a printing cycle and to positively move said printing member into printing position and return this to retracted position during said printing cycle, a second guard member disposed alongside said printing member and adapted to move into said printing throat in advance of said printing member and hold an object to be printed against said platen; and means for positively operating said second guard member from said shaft.;

and that the said Letters Patent should be read with this correction therein that the same may conform to the record of the case in the Patent Office.

Signed and sealed this 11th day of October, A. D. 1932.

(Seal)

M. J. Moore,
Acting Commissioner of Patents.
